UNITED STATES PATENT OFFICE.

HERBERT L. MOSHER, OF DOWAGIAC, MICHIGAN, ASSIGNOR OF ONE-HALF
TO FRED E. LEE, OF SAME PLACE.

DESIGN FOR A HEATING-STOVE.

SPECIFICATION forming part of Design No. 24,891, dated November 12, 1895.

Application filed November 15, 1894. Serial No. 528,926. Term of patent 14 years.

To all whom it may concern:

Be it known that I, HERBERT L. MOSHER, a citizen of the United States, residing at the city of Dowagiac, in the county of Cass and State of Michigan, have invented a certain new and useful Improved Design for Heating-Stoves, of which the following is a specification.

My invention relates to a design for heating-stoves.

It relates more particularly to the body of the stove exclusive of the top, as illustrated complete in the accompanying sheet of drawing, which presents a perspective view of a stove made in accordance with my design, the one view being considered sufficient to thoroughly illustrate my design.

The leading feature of my design consists of a stove-body which is substantially cylindrical in its general contour, which is supported by the metal bars H, which are in the form of spirals I at the bottom to form ornamental legs, and the tops of said bars are in the shape of spirals I' to correspond to the lower spirals I for ornamentation purely. A horizontal band A is shown around the central portion of the stove, at which point the stove is separable into two parts. These bars

H are constructed of ornamental black oxidized iron or steel, and in connection with the 30 cylindrical body of the stove give to the same a very artistic appearance. It is not material to my design, as here shown, whether the main parts of the body of the stove are left plain or are ornamented in any suitable way. This 35 design is the general outline of the stove.

Having thus described my design, what I claim is—

1. The design for a heating stove as herein described and shown. 40
2. In the design for a stove the upper or heating chamber, as herein shown and described.
3. In the design for a heating stove the lower or fire chamber, as herein described and 45 shown.
4. In the design for a heating stove the leg, as herein described and shown.

In witness whereof I have hereunto set my hand and seal in the presence of two witnesses. 50

HERBERT L. MOSHER. [L. S.]
